United States Patent Office.

IMPROVEMENT IN FRICTION PULLEY.

CHARLES B. SMITH, OF NEWARK, NEW JERSEY, ASSIGNOR TO WRIGHT & SMITH, OF SAME PLACE.

Letters Patent No. 60,269, dated December 4, 1866.

SPECIFICATION.

TO ALL WHOM IT MAY CONCERN:

Be it known that I, CHARLES B. SMITH, of Newark, in the county of Essex, and State of New Jersey, have invented a new and improved Friction Pulley or Coupling; and I do declare that the following is a full and exact description thereof, reference being had to the accompanying drawings, and to the letters of reference marked thereon.

To enable others skilled in the art to make and use my invention, I will proceed to describe its construction and operation.

In Figure 1, of accompanying drawing, A represents the rim of a pulley, the inside of which is turned to a true surface. B represents a block secured to the shaft, C, by a set-screw at D. E' and E'' represent levers held in position by and moving on axis of bolt F, which is connected to block B. G represents a spring fastened to block B and resting on levers E' and E''. H represents a wedge or bar, as shown at H in fig. 3, fastened into the sliding-block J, which slides loosely upon shaft C. I' and I'' represent set-screws passing through levers E' and E'', the points of which rest upon wedge H.

Figure 2 is a side view of the same, A representing the rim of the pulley, B the block, D the set-screw securing the same to the shaft C; E' and E'' are the levers; F bolt; I' set-screw in the lever E'; H represents the wedge.

The operation is as follows: When the sliding-block J is thrown out from the pulley, the spring G forces the levers E' and E'' inward, and the pulley A runs loosely upon the shaft. But when the sliding-block J is thrown in and the wedge H is driven between the set-screws I' and I'', the levers E' and E'' are forced outward, causing the extremities at K', K'', K''', and K'''' to press powerfully against the inner rim of the pulley, thus making it fast upon the shaft C. I have shown and described the levers E' and E'' as being forced outward by means of a wedge. The same effect may be produced by a cam working in the block D.

Having thus described my invention, what I claim as my invention, and desire to secure by Letters Patent, is—

The combination of levers E' and E'', block B, sliding-block J, wedge H, or its equivalent, bolt F, and set-screws I' and I'', for the purpose set forth.

CHARLES B. SMITH.
